UNITED STATES PATENT OFFICE

2,313,366

CARBURETOR

William Schwier, Milwaukee, Wis.

Application May 28, 1941, Serial No. 395,661

1 Claim. (Cl. 261—41)

This invention aims to provide a carburetor characterized by novel means for controlling the idling flow of fuel and the running flow of fuel consonantly with the operation of an air controlling valve, the fuel being discharged through a nozzle, and a novel venturi and cone valve structure being provided for regulating the downward flow of air about the nozzle.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows, in vertical section, a carburetor constructed in accordance with the invention, parts being removed;

Fig. 2 is a side elevation;

Fig. 3 is a side elevation, at right angles to the showing of Fig. 2;

Fig. 4 is a cross section on the line 4—4 of Fig. 1;

Fig. 5 is a perspective disclosing one of the shafts and the cam which it carries.

The carburetor forming the subject matter of this application comprises a tubular body 1, including a bowl 2, connected by a tapered portion 3 with a reduced tubular neck 4, having an attaching flange 5.

A shaft 6 is mounted to rock in the upper portion of the bowl 2 and carries an air valve 7, disposed within the bowl, the shaft being supplied with an upstanding arm 8, whereunto is connected an actuating means 9.

The numeral 10 designates a Venturi member, embodying a flared bell 11, extended into the bowl 2, the bell being provided with a tubular extension 12, slideable in the neck 4 of the body 1, a compression spring 14 being interposed between the bell 11 and the tapered portion 3 of the body 1.

A tubular nozzle carrier 15 is located in the vertical axis of the body 1. The means for supporting the nozzle carrier 15 can be more conveniently described hereinafter. A nozzle 16 is threaded into the nozzle carrier 15, and is pro-

vided with a closed top. Intermediate its ends, the nozzle 16 is reduced, to form a circumscribing space 17 within the nozzle carrier 15. The nozzle 16 is equipped with transverse ports 18, leading from the space 17 to the bore of the nozzle 16.

The lower portion of the nozzle 16 is surrounded by a downwardly tapered cone valve 19, the top 20 of which is supplied with openings 21. The top 20 of the cone valve 19 has a tubular neck 22, whereby the cone valve is mounted on the nozzle carrier 15 for limited vertical movement. The neck 22 is supplied with vertically elongated slots 23, receiving pins 24, mounted in the nozzle carrier 15. The cone valve 19 is adapted to engage the Venturi member 10, at the restricted opening which is located at the junction between the bell 11 and the extension 12.

The nozzle carrier 15 has a lateral arm 25, engaging the inner surface of the bowl 2. The arm 25 of the nozzle carrier 15 is provided with a lower chamber 26 and an upper chamber 27, connected by a passage 28. Access is had to the chamber 27 and to the passage 28 and to the chamber 26 by removing a closure plug 29 that is threaded into the arm 25. Fuel is delivered into the lower chamber 26 through a conduit 30, mounted in the bowl 2 and in the arm 25.

A tubular guide 31 extends through the lower chamber 26, the inner end of the guide being threaded into the arm 25 of the nozzle carrier 15, the guide being provided at its outer end with a head 32, which engages the outer surface of the bowl 2. Thus, the nozzle carrier 15 and its arm 25 are secured within the bowl. The guide 31 is provided with transverse ports 33, communicating with the lower chamber 26. At the inner end of the bore of the guide 31 there is a valve seat 34. A port 35 in the nozzle carrier 15 leads from the valve seat 34 to the space 17 about the nozzle 16. A needle valve 36 is slidably mounted in the guide 31 and cooperates with the seat 34.

As to the upper chamber 27, the parts last hereinbefore described are duplicated, and reference to them may be reduced to a mere catalogue. They comprise a tubular guide 41, having a head 42, the guide being provided with ports 43 and a valve seat 44. The port 45 corresponds to the port 35, and the needle valve is shown at 46.

The numeral 47 marks a cross head, a pull spring 48 connecting the lower part of the cross head with the carburetor body 1. The needle valve 36 is adjustably mounted in the cross head 47, but is held firmly thereto by the clamping nuts 49. A wear ring 50 is carried by the needle valve 36 and abuts against the innermost nut 49.

The needle valve 46 passes through an enlarged hole 51 in the cross head 47. An abutment nut 52 is threaded to a seat on the needle valve 46. A compression spring 53 is interposed between the cross head 47 and the abutment nut 52. An adjusting nut 54 is threaded on the outer part of the needle valve 46 and engages the outer surface of the cross head 47 under the thrust of the spring 53.

A crank arm 55 is held for adjustment, by means of a set screw 56, on the outer part of the shaft 6 which carries the air valve 7. A link 57 is provided. The link 57 embodies means 58 whereby the length of it can be changed. The upper part of the link 57 is pivoted at 59 to the crank arm 55 on the shaft 6.

The lower part of the link 57 is pivoted at 60 to a crank arm 61 on a transverse shaft 62, mounted to rock in a tubular bearing 63 which forms part of a bracket 64, fixed on the bowl 2 of the carburetor body 1. A forked cam 65 is held for adjustment on the shaft 62, by means of a set screw 66. The cam 65 straddles the lower needle valve 36 and bears against the wear ring 50.

By an adjustment secured through a proper manipulation of the adjusting nut 54, and the nuts 49, the idling needle valve 46 may be caused to be open, to such a degree as to permit idling, whilst the needle valve 46 is closed under the pull of the spring 48 on the cross head 47.

Then there exists an open idling passage including the conduit 30, the lower chamber 26, the ports 33 in the guide 31, the opening 28, the upper chamber 27, the ports 43 in the guide 41, the port 45, the space 37 about the nozzle 16, the nozzle ports 18, and the bore of the nozzle 16.

The running passage is closed by the needle valve 36 and includes the conduit 30, the lower chamber 26, the ports 33 in the guide 31, the port 35, the space 37 about the nozzle 16, the nozzle ports 18, and the bore of the nozzle 16.

When the shaft 6 is operated by the means shown at 8-9, the needle valve 36 is retracted to open the running passage, and the needle valve 46 is retracted to open the idling passage more widely, by a train of parts including the shaft 6, the crank arm 55, the link 57, the crank arm 61, the shaft 62 and the cam 65, which transmits movement to the needle valves 36 and 46, in a way which will be clear from Fig. 1 of the drawings. The valves 46 and 36 move outwardly together.

In Fig. 1, the needle valves 36 and 46 are shown open, in order to display the structure more clearly, but suppose that, by a proper manipulation of the nut 54, the needle valve 46 is so disposed that it will be open when the needle valve 36 is closed. Due to engine suction, there exists in the lower portion of the body 1, a region 67 of low pressure. The venturi 10 does not move downwardly, responsive to low pressure in the region 67, because the venturi is sustained by the spring 14, the valve 7 being opened only enough to supply air for idling purposes, and the pressure in the bowl 2 being insufficient to overcome the action of the spring 14.

There is now a strong suction through the passage beginning with the bore of the nozzle 16, and including the port 45, the bore of the

guide 41, the ports 43, the opening 28, and the chamber 26, fuel supplied by the conduit 30 being drawn upwardly and discharged into the bore of the nozzle 16.

As the air valve 7 is opened, atmospheric pressure above the bell 11 of the venturi 10 increases. The venturi 10 moves downwardly, against the action of the spring 14, and the cone valve 19 at first moves downwardly with it. The first thing that takes place is a spacing of the cone valve 19 from the lower end portion of the nozzle 16, and a downward passage of air is afforded, through the openings 21 in the top of the cone valve and in the space that exists between the lower part of the cone valve and the lower part of the nozzle 16.

As the venturi 10 continues to move downwardly, responsive to atmospheric pressure above it, the downward movement of the cone valve 19 ultimately is stopped by the pins 23 on the nozzle carrier 15 and then there is created a second air passage, to wit, a passage between the flared bell 11 of the Venturi member 10 and the cone valve 19.

Broadly considered, the operation of the venturi 10 and the cone valve 19 is described in my Patent No. 2,163,499, issued June 20, 1939, although in that patent, a downward movement of the venturi is brought about mechanically.

When the cam 65 is moved toward and to the position of Fig. 1, the valves 36 and 46 move inwardly together. The valve 36 closes, to shut off the running supply, before the valve 46 closes completely, the valve 46 remaining open sufficiently for idling purposes, it being recalled that, as has been set forth hereinbefore, by a proper manipulation of the nut 54 the valve 46 has a retracted position with respect to the valve 36. The purpose of the spring 53 is to draw the nut 54 against the cross head 47, thereby aiding in preventing the nut 54 from unthreading. The spring 53 permits a longitudinal adjustment of the valve 46 to be made, through the instrumentality of a single nut, namely the nut 54.

What is claimed is:

A carburetor comprising a body, a nozzle carrier in the body, a fuel nozzle supported by the carrier, there being upper and lower chambers in the carrier, a source of fuel supply for the lower chamber, the carrier being provided with an opening connecting the chambers, upper and lower tubular guides extended across the respective chambers and in communication with the nozzle, the guides having openings communicating with the respective chambers, upper and lower needle valves slidable in the respective guides and controlling the flow of fuel through the guides to the nozzle, the upper valve being an idling valve, and the lower valve being a running valve, an air controlling valve in the body, above the nozzle, a cross head, means for connecting the lower needle valve fixedly but adjustably to the cross head, the upper needle valve passing through the cross head, for longitudinal sliding adjustment, spring means connected to the cross head for closing the valves, and mechanism operated in consonance with the air valve for opening the upper and lower needle valves.
